(57) **CLAIM**

The ornamental design for a heat sink for a head mounted device, as shown and described.

DESCRIPTION

FIG. 1 is a top, front, and right side perspective view of a heat sink for a head mounted device.

FIG. 2 is a top plan view thereof.

FIG. 3 is a front elevation view thereof.

FIG. 4 is a left side elevation view thereof.

FIG. 5 is a right side elevation view thereof; and,

FIG. 6 is a top, rear, and right side perspective view thereof.

The broken lines shown in the drawings illustrate environment and form no part of the claimed design.
